United States Patent Office.

RICHARD PATTIN, OF MARIETTA, OHIO.

Letters Patent No. 61,092, dated January 8, 1867.

IMPROVEMENT IN LAMP-CHIMNEY CLEANERS.

The Schedule referred to in these Letters Patent and making part of the same.

TO ALL WHOM IT MAY CONCERN:

Be it known that I, RICHARD PATTIN, of Marietta, in the county of Washington, in the State of Ohio, have invented a new and improved Device for Cleaning Lamps and Lanterns; and I do hereby declare the following is a full, clear, and exact description of the construction and operation of the same, reference being had to the annexed drawings, making part of this specification, in which—

Figure 1 is a side elevation of my invention without the metal strips.

Figure 2, a side elevation with metal strips extended; and

Figure 3, the same with strips in globular form.

This invention consists of two pieces of wire, one of which slides freely in curvatures formed in the other, and of elastic metallic strips connecting two contiguous ends of the two pieces of wire, for the purpose of cleansing lamp chimneys, etc., in the manner hereinafter fully described.

H represents one of the pieces of wire, of any convenient dimensions, one end of which is bent into a ring, A, for convenience of manipulation, and the other into a ring or eye, E, at right angles to the first. K represents the other piece of wire, one end of which is formed into a handle, B, at right angles with the main body of the wire, and the other end into an eye of the same size, and parallel with the eye E. C and D represent eyes formed in the body of the wire K, equal in size, and parallel. The eyes E and F are of somewhat greater diameter than the eyes C and D. The wire H passes through the eyes C and D, and slides freely therein. The wire K passes through the eye E. The two wires are thus connected, in the manufacture of the instrument, beyond the possibility of disjunction, except in case of the breaking or straightening of at least one of the eyes. G G represent the elastic metallic strips before spoken of, which are usually six in number, and of such dimensions as may be desired. A length of four inches will be found usually most convenient. The strips are united in any suitable manner, at one end to the eye E, and at the other to the eye F, and are placed at equal distances apart. They should be nearly or quite straight when not under pressure. To them are to be attached rags or other suitable cleansing material.

From this description of the construction of this instrument, the manner of its operation will appear clear. The elastic strips, with the rubbing material attached, are to be introduced within the chimney to be cleansed. The operator then, holding in one hand the ring A, and by the other the handle B, presses the former towards the latter, by which pressure the eye E is caused to approach the eye F, and consequently the metallic strips G assume a curved form, and bring the rubbing material in contact with the inner surface of the chimney. It is then only necessary to give the instrument a few turns to effect the cleansing process. Pressure having then been removed, the metallic strips, by virtue of their elasticity, return to their former position, and the instrument may be withdrawn. It will thus be seen that this forms a cheap, simple, and effective instrument for accomplishing the purpose for which it is designed. In its manufacture the wire H having first been provided with the ring A and the eye E, and the wire K with the handle B, the latter wire is bent round the former, so as to form the eyes C and D, its point passed through the eye E, and the eye F then formed on it. The strips G are afterward attached.

What I claim, and desire to secure by Letters Patent, is—

1. Forming the rings or eyes by which the two wires are connected, out of the body of the wires, instead of additional pieces, in the manner set forth.
2. The wires H and K, arranged to move freely one upon the other, in combination with the elastic metallic strips G, substantially as described.

RICHARD PATTIN.
